Patented Apr. 13, 1926.

UNITED STATES PATENT OFFICE.

FRANK BRISCOE, OF JACKSON, MICHIGAN, ASSIGNOR, BY MESNE ASSIGNMENTS, TO
BRISCOE DEVICES CORPORATION, OF PONTIAC, MICHIGAN, A CORPORATION OF
MICHIGAN.

CARBURETOR.

Application filed March 3, 1919. Serial No. 280,333.

To all whom it may concern:

- Be it known that I, FRANK BRISCOE, a citizen of the United States of America, residing at Jackson, in the county of Jackson and 5 State of Michigan, have invented certain new and useful Improvements in Carburetors, of which the following is a specification, reference being had therein to the accompanying drawings.
- 10 The invention relates to carburetors of that type in which the air is controlled by a hinged shutter extending obliquely across the air conduit to the extent of forming in effect a Venturi tube of variable open area, 15 in co-operation with means for discharging the liquid fuel into said Venturi tube and for variably metering the fuel by the movement of said shutter.
- It is the object of the present invention to 20 improve the operation of such carburetors by the introduction of a dash-pot for controlling movement of the air shutter and fuel metering means. And it is a further object to obtain the improved results without complication in construction. The invention, therefore, comprises various features as hereinafter set forth.
- In the drawings:
- Figure 1 is a longitudinal section of the 30 carburetor;
- Figure 2 is a similar view, showing a modified construction;
- Figure 3 is a section on line 3—3 Figure 2.
- A is the casing of a carburetor having the 35 air conduit B extending therethrough and provided with a depending hollow stem C to which the cup D for the float chamber is attached by means of the nut E engaging the threaded lower end of the stem. Within 40 the air conduit is arranged the shutter F which normally extends in inclined position across said conduit, being pivotally supported at G. The arrangement is such that the pressure of incoming air will lift the free end of the shutter, swinging the same about its pivot into a less acute angle and thereby 45 enlarging the open area. H is a metering plunger which slidably engages the hollow stem C. The upper end of this plunger H is provided with a yoke-shaped head I which 50 embraces the free end of the shutter F so as to form a coupling engagement therewith by which the plunger will be lifted upon the
- opening of the shutter. The head I has an aperture J therethrough which is in alignment with a slot K in the shutter, permitting a small quantity of air to pass therethrough when the shutter is closed. The plunger H is hollow, the chamber therein being supplied with liquid fuel from the float chamber D and a port L at the upper end of the plunger communicating with said chamber discharges directly into the restricted air port J. M is a screw adjustably 55 engaging the head I in alignment with the port L and which may be adjusted to vary the liquid discharged through said port. The plunger H is further provided with a tapering side N forming a second discharge 60 for the liquid and which is progressively increased in area as the plunger is lifted. Thus, when the shutter F is closed, as in idling position, the passage of the air is confined to the restricted aperture J and the liquid fuel is discharged into said passage 65 through the restricted aperture L. When, however, the shutter F is opened by increased differential air pressure acting thereon the air passage is enlarged and at the same time liquid fuel is discharged through 70 the metering passage in proportion to the volume of air.
- The construction as thus far described has 75 been heretofore used and in operation the shutter F and metering plunger H have been lifted by air pressure and returned by gravity. To overcome the greater lag in the liquid, it is desirable to retard the opening movement of the air shutter by suitable 80 means, such as a dash-pot, but it is difficult 85 to introduce such an element without complicating the construction. I have, therefore, devised a construction avoiding such 90 complication, which is as follows:
- The hollow plunger H is closed at its 95 lower end and is so fitted in the hollow stem C as to form a dash-pot. This requires provision of means for supplying the liquid fuel both to the interior of the hollow stem and to the metering passage formed by the 100 tapered side N. Both of these results are accomplished by forming the hollow stem C with upper and lower portions fitting the plunger H and with a channel O between 105 said portions communicating through ports P with the liquid fuel in the chamber D.

- The channel O communicates with the interior of the hollow plunger H preferably through a series of ports Q, Q', etc., which are successively registered with said channel as the plunger is lifted. There is also a port R through the wall of the hollow plunger establishing communication between the interior thereof and the metering channel formed by the tapered side N.
- 10 Thus, in each position of adjustment of the plunger H there will be a supply of liquid fuel to the interior thereof through one of the ports Q, Q', etc., a portion of which supply is discharged through the port L while another portion will be discharged through the ports R and metering passage into the air conduit. Inasmuch, however as the well within the hollow stem is filled with the liquid fuel the plunger cannot be moved without a displacement of the liquid. Such displacement can be effected either by providing a clearance between the plunger and the hollow stem or by a restricted passage between the float chamber and the chamber below the stem. The latter construction is shown in Figure 2, in which S is a restricted passage through the wall of the hollow stem C leading from the float chamber to a chamber T beneath the plunger H. This chamber is formed in a hollow member E' which also forms the nut for clamping the cup D of the float chamber against a shoulder C' on the hollow stem C. A drainage cock U may be attached to the member E' permitting the removal of water or sediment therefrom.
- 25 In the construction shown in Figure 1 instead of a restricted passage S a slight clearance is provided between the plunger H and the hollow stem C, so that leakage of the liquid through the clearance will per-

mit of the slow movement of the plunger. To facilitate this construction and also form an easy method of producing the annular channel O, the hollow stem C is provided with a pair of bushings V and V' which are cast or otherwise secured therein respectively above and below the channel O. The upper bushing V may be made a comparatively close fit to the portion of the plunger sliding therein, while the lower bushing is formed with the desired clearance around the plunger that will permit the required displacement of the liquid.

With the construction above described the plunger H may be inserted into or removed from the hollow stem by providing an opening W in the upper side of the casing A, said opening being closed by a cap member W'. This will facilitate the assembly of the parts and also adjustment of the same as required in setting the carburetor.

What I claim as my invention is:

In a carburetor, the combination with an air conduit, of a valve therein for restricting said conduit and opened by the pressure of air passing therethrough, a cylindrical well beneath said conduit and opening thereto, bushings in the upper and lower portion of said well spaced from each other to form an annular channel therebetween, and a hollow plunger extending from said conduit into said well, being connected to said air valve to be operated thereby, said plunger being closed at its lower end, having a series of apertures intermediate its ends for establishing communication between said annular chamber and the interior of the plunger in different positions of adjustment thereof.

In testimony whereof I affix my signature.

FRANK BRISCOE.
